CLAIM

The ornamental design for a life jacket, as shown and described.

DESCRIPTION

FIG. 1 is a front, right and top side perspective view of a first embodiment of a life jacket, showing our new design; FIG. 2 is a back, right and top side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a front, right and top side perspective view of a second embodiment of a life jacket, showing our new design;

FIG. 8 is a back, right and top side perspective view thereof; FIG. 9 is a front elevational view thereof; FIG. 10 is a rear elevational view thereof; FIG. 11 is a left side elevational view thereof; and, FIG. 12 is a right side elevational view thereof.

The broken lines in the drawings illustrate the portions of the life jacket, which form no part of the claimed design.
